UNITED STATES PATENT OFFICE

JOSEPH G. SOLA, OF CHICAGO, ILLINOIS, ASSIGNOR TO SOLA CORPORATION, OF CHICAGO, ILLINOIS, A CORPORATION OF ILLINOIS

ELECTRIC TRANSFORMER

Application filed March 1, 1930, Serial No. 432,329. Renewed December 21, 1931.

This invention relates to an electric transformer, and an object is the provision of a transformer provided with an automatically operative protection relay adapted to break the circuit of the primary winding when the load on the secondary winding has been reduced to a predetermined value. More specifically, an object of the invention is the provision of an improved type of transformer provided with primary and secondary windings, and having an auxiliary secondary winding adapted when connected with a controlling coil of a circuit breaker interposed in the primary coil circuit to cause such circuit breaker to open the circuit through the primary coil when the secondary coil circuit is opened or the load thereon is cut down to a predetermined point, but arranged so that when there is a normal load on the secondary coil circuit said circuit breaker shall fail to break such primary coil circuit. It is one of my objects to provide an arrangement of this type in which the controlling coil of the circuit breaker exerts a pull on an armature of the circuit breaker for opening the primary coil circuit, with the arrangement such that when the load on the secondary coil circuit is normal the controlling coil is unable to operate the circuit breaker but that when the load is cut down to a predetermined minimum or when the secondary coil circuit is opened the pull on the armature becomes sufficiently strong for causing the circuit breaker to operate.

It is one of the objects of my invention to provide an arrangement of this type comprising means for limiting the magnitude of the current through said two secondary coils so as to insure that there shall be the desired differential strength of pull by said controlling coil for attaining the desired results as above explained.

Other objects will appear hereinafter.

The invention consists in the combinations and arrangements of parts hereinafter described and claimed.

The invention will be best understood by reference to the accompanying drawing forming a part of this specification, and in which:

Fig. 1 is a diagrammatic illustration of the parts and devices employed, including the transformer and the respective windings; and

Fig. 2 is an end elevational view of the transformer proper.

As illustrated, the preferred embodiment of the invention comprises a transformer in the form of a rectangular core frame, preferably laminated in structure, and having two parallel lateral yoke portions 4 and 5, with connecting parallel end portions 6 and 7. Extending substantially midway between portions 4 and 5 is a winding core 8 comprising a primary core limb 9 and a secondary core limb 10. Extending laterally from the winding core 8, transversely of the core and in a direction toward the yoke portions 4 and 5, respectively, are two shunt arms 11 and 12. By reference to Fig. 1 it will be noted that shunt arms 11 and 12 do not terminate in contact with the yoke portions 4 and 5, respectively, but are spaced a slight distance therefrom to provide gaps.

In the present embodiment of the invention, the primary and secondary windings are in longitudinal alignment. Primary input wires 13 and 14 are connected to a primary winding 15 on the core part 9, and a secondary winding 16 on the core part 10 is connected to output wires 17 and 18. Connected in the lead 14 so as to be in the primary circuit exteriorly of the transformer, is a circuit breaker 19 having an armature 20 adapted to be actuated by a controlling coil 21 when the latter receives a sufficient supply of current. It will be noted that coil 21 is not connected with either the primary circuit or the secondary circuit, but is connected by wires 22 and 23 to an auxiliary winding 24 composed of a few turns of relatively heavy wire on the core limb 10 adjacent the yoke end portion 7.

In operation, with the normal load connected across the terminals of the secondary coil 16, the flux set up in the core limb 9 by the current through the primary coil 15 is divided, part of such flux flowing through the core limb 10 and threading the secondary coil 16 and the remaining portion being di-

verted from the core portion 10 to the shunt arms 11 and 12 and across the air gaps at the ends of said shunt arms, the strength of flux required through the core leg 8 for forcing a substantial proportion of such flux to pass through the shunt arms and across the air gaps depending on the size of the air gaps. As the air gaps are narrowed, the maximum limitation with respect to the current which will flow through the coils is correspondingly lowered, a reduction in the size of the air gaps serving to cut down the reluctance of the shunt return path through the arms 11 and 12 for the flow of the magnetic flux therethrough without threading the secondary coils 16 and 24. As such flux is diverted from the secondary coils, the strength of the current through such secondary coils is correspondingly lowered, and such lowering of the current flowing through the secondary coils acts as a limitation with respect to the flow of current through the primary coil. By regulating the size of the air gaps, accordingly, I am able arbitrarily to limit the strength of current handled by the transformer.

With such current limiting means in use, I am enabled to make the coil 24 of comparatively heavy wire and of a comparatively small number of turns without danger of undue heating, arranged so that when the circuit is closed through the secondary coil 16, with a portion of the flux flowing through the shunt arms 11 and 12, the current through the coil 24 is very small so as to produce only a slight pull on the armature 20 by the coil 21. The arrangement is such, however, that when the secondary coil circuit is opened so as to cause the counter magnetic flux pressure established by the current through such coil to be eliminated substantially the entire flux flowing through the core leg 9 flows also through the core leg 10 without any substantial diversion of flux through the shunt arms 11 and 12, causing an increase in the current through the coil 24 sufficiently for enabling the coil 21 to operate the circuit breaker for opening the primary circuit through the coil 15.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In an arrangement of the type described, the combination of core means, a primary coil and a secondary coil in transformer rela-

tionship to each other on said core means, an auxiliary coil on said core means, shunt core means including an air-gap located between said primary and said secondary coils adapted when the secondary coil circuit is opened to cause a variation in the strength of the flux threading said auxiliary coil, and means in operative relation with said auxiliary coil adapted automatically to open said primary coil circuit by reason of the change in the strength of the current through said auxiliary coil when said secondary coil circuit is opened. 70 75

2. In an arrangement of the type described, the combination of core means comprising a rectangular yoke portion, a transverse core member extending between two sides of said yoke portion, a primary winding on said transverse core member at one end portion thereof, a secondary winding and an auxiliary winding on said transverse core member in end to end relation to said primary winding, a circuit breaker connected with the primary winding circuit, an operative connection between said circuit breaker and said auxiliary winding, and a magnetic flux shunt arm including an air gap extending laterally from said core member between said primary and secondary windings. 80 85 90

3. In an arrangement of the type described, the combination of core means comprising a rectangular yoke portion, a transverse core member extending between two sides of said yoke portion, a primary winding on said transverse core member at one end portion thereof, a secondary winding and an auxiliary winding on said transverse core member in end to end relation to said primary winding, a circuit breaker connected with the primary winding circuit, an actuating coil on said circuit breaker connected to said auxiliary winding, and a magnetic flux shunt arm including an air gap extending laterally from said core member between said primary and secondary windings. 95 100 105 110

4. In an arrangement of the type described, the combination of core means, a primary coil and a secondary coil in transformer relationship to each other on said core means, an auxiliary coil on said core means, means adapted through the action of the counter magnetic flux pressure set up by the secondary current when the secondary coil circuit is closed to divert from said auxiliary coil a portion of the flux set up by the current through said primary coil and arranged so that when the secondary coil circuit is opened said flux is caused to thread said auxiliary coil, and means adapted automatically to open said primary coil circuit by the action of the increased current through said auxiliary coil when said secondary coil circuit is opened. 115 120 125

5. In an arrangement of the type described, the combination of core means comprising a core bar, return path means connecting the 130

- end portions of said bar; and an arm providing a shunt return path including an air gap from said bar to said first named return path means; a primary coil and a secondary coil 5 in transformer relationship to each other on said core bar on opposite sides of said arm; an auxiliary coil on said core bar in such arrangement that when the secondary coil circuit is closed a portion of the flux set up by the current through the primary coil is diverted from said auxiliary coil and arranged so that when the secondary coil circuit is opened said flux is caused to thread said auxiliary coil; and means adapted automatically 10 to open said primary coil circuit by the action of the increased current through said auxiliary coil when said secondary coil circuit is opened.
6. In an arrangement of the type described, 20 the combination of a core bar, a primary coil on said core bar, other core means providing an all-metal return path for the magnetic flux through said core bar, a secondary coil on said core, a core arm extending between said two coils comprising a shunt connection from said core bar to said other core means and including an air gap therein adapted when the secondary coil circuit is closed to divert from the secondary coil a substantial 25 part of the flux threading the primary coil, an auxiliary coil on said core in secondary relationship to said primary coil, circuit means including a switch connected with said primary coil, and means in operative relationship with said auxiliary coil adapted automatically to open said switch upon the change in the strength of the current through said auxiliary coil produced by the opening 30 of the secondary coil circuit.
7. In an arrangement of the type described, 35 the combination of core means comprising two core bars in spaced relation to each other, cross-bars joining the ends of said first named bars, and a core arm including an air gap joining said first named bars at an intermediate point; a primary coil on one of said first named bars at one side of said core arm; a secondary coil and an auxiliary coil in end to end relation with said primary coil and 40 on the same core bar with said primary coil but at the opposite side of said core arm; and means in operative relation with said auxiliary coil adapted automatically to open said primary coil circuit by reason of the increase 45 in the strength of the current through said auxiliary coil when said secondary coil circuit is opened.
8. In an arrangement of the type described, 50 the combination of core means comprising two core bars in spaced relation to each other, cross-bars joining the ends of said first named bars, and a core arm including an air gap joining said first named bars at an intermediate point; a primary coil on one of said first 55 named bars at one side of said core arm; a secondary coil and an auxiliary coil in end to end relation with said primary coil and on the same core bar with said primary coil but at the opposite side of said core arm; a circuit breaker connected in series with said primary coil; and a controlling coil connected with 60 said auxiliary coil and adapted automatically to operate said circuit breaker for opening said primary coil circuit by the increased current through said auxiliary coil when said secondary coil circuit is opened.
- In testimony whereof I have signed my name to this specification.
